DEVICE FOR PRODUCING CURRENT PULSES

Henry L. Mills, Minneapolis, Minn., assignor to
Guy L. Pugh, Minneapolis, Minn.

Application October 28, 1938, Serial No. 237,440

2 Claims. (Cl. 172—126)

5 My invention relates to devices for producing current pulses and has for an object to provide an extremely simple and inexpensive device capable of periodically producing at predetermined time intervals current pulses of short duration.

Another object of the invention resides in providing a device with which the current consumption is extremely low.

Another object of the invention resides in providing a device in which a transformer is used, energized by a source of direct or alternating current and in which high tension current is produced through periodically making and breaking the circuit from the source.

15 A feature of the invention resides in providing the transformer with a core having oppositely facing poles at the end thereof and in providing an armature having end members adapted to swing past said pole pieces.

20 An object of the invention resides in guiding said armature so that the portions thereof which cooperate with the poles of the core swing at right angles to the direction of travel of the flux and past the poles.

25 A still further object of the invention resides in constructing the armature U-shaped in form.

Another object of the invention resides in providing a balanced armature.

30 An object of the invention resides in arranging the poles of the core and the members of the armature cooperating therewith so that force is exerted upon the armature of diametrically opposite localities.

35 A feature of the invention resides in providing the device with a U-shaped standard adapted to straddle the transformer and to which the armature is pivoted.

40 Other objects of the invention reside in the novel combination and arrangement of parts and in the details of construction hereinafter illustrated and/or described.

In the drawings:

Fig. 1 is a plan view of a device for producing current pulses and illustrating an embodiment 45 of my invention.

Fig. 2 is a view similar to Fig. 1 showing the parts in altered position.

Fig. 3 is a side elevational view of the device with the parts arranged as shown in Fig. 2.

50 Fig. 4 is an end elevational view of the structure shown in Figs. 2 and 3.

Fig. 5 is a cross sectional view taken on line 5—5 of Fig. 2 and drawn to a greater scale.

Fig. 6 is a wiring diagram of the invention.

55 In electrifying fences or the operation of flash

signals in isolated localities, a high voltage is required which is most advantageously procured where alternating current is available. However, availability of alternating current on farms and in isolated localities is rather limited. The present invention provides a device which may utilize current from any source and particularly direct current as procured from a storage battery or a farm lighting plant and is so designed as to economize on the current consumption so as 10 to render the use of the device very inexpensive.

My invention consists of a base 10 which may be constructed of metal or any other suitable material. Mounted on this base is a standard 11 U-shaped in construction which is formed 15 with two upstanding legs 12 and 13 and a cross bar 14 connecting the same. The standard 11 is preferably constructed of sheet metal which is channel shaped in cross section and formed with a web 15 and flanges 16 extending therefrom. The flanges 16 are mitered at the corners where the standard is bent to form the legs and cross bar as indicated at 17. For the purpose of attaching the standard to the base 10 the web 15 is bent outwardly to provide feet 18 which are 20 bolted to the said base by means of bolts 19. By means of this construction a space 21 is provided within the standard proper, which space is utilized in a manner to be presently more fully described. 25

Within the space 21 of standard 11 is disposed a transformer 22. This transformer consists of a core 23 constructed of strips of sheet iron elongated in form and assembled to form a unitary core structure. Upon this core is wound windings 24 which will be subsequently fully described. 30

The core 23 is so constructed that the ends 35 37 and 38 thereof are exposed and form poles facing in opposite directions.

The core 23 is supported by means of two clips 40 41 and 42. These clips being identical in construction, only the clip 42 will be described in detail which is clearly shown in Fig. 4. This clip is constructed from a strip of metal which is bent to provide two legs 43 and 44 which straddle the sides of the core 23 and which are connected together by means of a cross member 45. A bolt 46 extends through the said legs 43 and 44 immediately below the core 23 and holds the clip rigidly attached to the core. The legs 43 50 and 44 have feet 47 bent outwardly therefrom which rest upon the base 10 and are secured thereto by means of bolts 48.

Operating in conjunction with the core 23 is an armature 51 which is constructed from a 55

bar of iron bent to provide an elongated body portion 52 and two end members 53 and 54 depending therefrom. The end members are arranged in spaced parallel relation and are spaced 5 apart a distance slightly greater than the length of the core 23 to permit of swinging of the armature past said core as will hereinafter become more readily apparent.

The armature 51 is pivoted for movement in 10 a horizontal plane by means of a construction best shown in Fig. 5. Attached to the said armature at the center of the body portion 52 thereof is the outer race of a ball bearing 61. This ball bearing is pressed into a hole 62 in the 15 body portion 52 and is thus rigidly held in position. Extending through the inner race of the ball bearing is a screw 63 which is secured to the inner race by means of nuts 64 and 65. Spacer washers 66 and 69 are arranged adjacent 20 the said race and hold the nuts 65 away from the outer race. In addition a rather thin washer 67 is employed which is disposed between the washer 69 and the nut 65. A similar washer 68 is disposed on the other side of the nut 65. The 25 screw 63 is held attached to the cross bar 14 of the standard 11. This is accomplished in the following manner. In the center of the web 15 of said cross bar is a hole 71 through which the shank 72 of the bolt 63 extends. A lock 30 washer 73 is placed upon the said shank and a nut 74 screwed on said shank clamps the said bolt to the web 15 of said cross bar.

Acting between the standard 11 and the armature 14 is a spiral spring 75, similar to the springs 35 used in watches and clocks. The inner end 76 of this spring is constructed to fit about the nut 65 and engages the same and is held from rotation with respect to the standard 11 thereby. This spring lies between the two washers 67 and 40 68 and is held in place upon said nut by means of said washers. The other end 77 of said spring (Fig. 1) is hooked around an edge of the body 45 52 of armature 51 and serves to urge the armature to rotate in a clockwise direction as viewed in Fig. 2.

Operated by the armature 51 is a switch 78 which consists of a switch arm 79 and a leaf spring 81 cooperating therewith. The arm 79 has a contact 82 secured to the same and the 50 leaf spring 81 has a contact 83 secured to it. The arm 79 is formed with a lug 84 extending outwardly therefrom which is attached to the end member 54 of armature 51 by means of a screw 85. The leaf spring 81 is attached to the 55 leg 12 of standard 11 between two insulating blocks 87 and 88. The entire structure is supported on said leg by means of screws 89 which clear the said leaf spring and which are tapped into the web 15 of said leg. The switch arm 79 of leaf spring 81 is so arranged that the same 60 arrests movement of the armature 51 in a position such that the end members 53 and 54 of said armature are in position to be attracted by the poles 37 and 38 of the core 23. A screw 91 65 screwed into the body portion 52 of armature 51 is adapted to engage the head of a screw 90 screwed into the web 15 of the cross bar 14 of standard 11 and to limit swinging movement 70 of the armature in a counterclockwise direction.

70 For the purpose of balancing the armature 51, a slot 151 is formed in the body portion 52 thereof adjacent the end member 53. A bolt 152 extending through this slot may be adjusted radially to counter balance the weight of the arm 79 75 of switch 78.

Attached to the base 10 is a terminal block 92 which is constructed from insulating material and which is secured thereto by means of bolts 93. This insulating block has binding posts 94, 95, 96, 97, 98 and 99 mounted on it to which 5 the terminals of certain of the windings 24 may be attached, whereby the transformer is energized.

The windings 24 as shown in Fig. 6 include 10 three primary windings 26, 27 and 28 and a secondary winding 29 having a great many turns whereby a high voltage is procured across said secondary winding when the primary circuit is made or broken. The windings 26 and 27 are connected to a common conductor 32 which is 15 connected to the binding post 96. The two windings 27 and 28 are connected to a common conductor 33 which is connected to the leaf spring 81 of switch 78. The arm 79 of said switch is connected to the armature 51 which is in electrical contact with the standard 11. This standard is likewise in electrical contact with base 10 which in turn is in electrical contact with binding posts 95, 97 and 98. A circuit 101 shunts the switch 78 and contains a condenser 102 by 20 means of which the arcing across the contacts 82 and 83 of switch 78 is reduced. The other side of the winding 26 is connected by means of a conductor 34 with the binding post 94 and the other side of the winding 28 is connected by 25 means of a conductor 34 with the binding post 99. The winding 28 is wound for six volts, the winding 27 is wound for 32 volts and the winding 26 is wound for 78 volts. It will thus be readily seen that if a source of six volt current is 30 connected across binding posts 98 and 99 the 6-volt winding 28 is energized. Likewise, if a 32-volt source of current is connected across binding posts 96 and 97 the 32-volt winding is energized and if a 110-volt source of current is connected across posts 94 and 95 both windings 27 and 28 are energized. In each case the same voltage is procured across the winding 29.

The operation of the invention when used as a device for electrifying fences is as follows: 45 The source of current is connected to the respective binding posts and two flexible leads 35 which are connected to the winding 29 are also connected to the fence wire and to ground. The base 10 is also supported so that the same is 50 insulated from ground. If this is not possible standard 11 is insulated from base 10. In normal position the armature 51 occupies the position shown in Fig. 2. The circuit through the primary of the transformer is energized through 55 switch 78 and the two end members 53 and 54 of the armature are attracted by the poles 37 and 38 which causes the armature 51 to swing about the ball bearing 61. As soon as the switch 78 is open the core 23 is de-energized and no 60 force acts on the said armature. However, the armature through the momentum acquired by the movement given it by the first impulse continues to swing past the cores 37 and 38 and to store up energy in the spring 75. The armature 65 finally comes to rest and the stored energy in said spring causes the armature to return to normal position. If the force is too great, screw 91 limits the motion of said armature. As soon 70 as the contacts 82 and 83 are again closed, the cycle is repeated. As these contacts make and break, a high voltage is induced in the secondary 29 which is transmitted to the fence. When an animal leans up against the fence it will immediately be shocked and will rapidly move away 75

from the fence. Due to the continual making and breaking of the circuit alternate pulsations are provided which electrify the fence and produce shocks to the animals at regular intervals. 5 The intervals of the time are dependent upon the weight of the armature 51 and the stiffness of the spring 75. These can readily be selected to give any desired time interval so as to make the device as economical as may be practical in 10 the consumption of electrical current.

10 My invention may also be used as a flasher or intermittently operated signal. In such case the secondary 29 of the transformer is connected to a "Neon" tube or equivalent lighting device. 15

15 As the armature 51 oscillates the tube is periodically lighted so as to produce successive flashes.

20 The advantages of my invention are manifest. An extremely inexpensive and simple device is provided whereby fences may be electrified or lighting devices operated. The device operates positively and by the proper selections of weights and spring tension will give any suitable timing. The device uses a minimum amount of electric current and will operate on an automobile battery 25 for several months. My invention may be used with either direct or alternating current or with farm lighting plants or storage batteries.

25 Changes in the specific form of my invention, as herein disclosed, may be made within the 30 scope of what is claimed without departing from the spirit of my invention.

30 Having described my invention what I claim as new and desire to protect by Letters Patent is:

1. A device for producing current pulses comprising an elongated open core having poles at the ends of the same, windings on the intermediate portion of said core, a base, means for securing said core and windings to the base, an armature constructed from a bar bent to form 35 an elongated body portion and end portions depending therefrom and disposed so as to cooperate with the ends of the core, a frame member straddling said core and windings and secured to said base, means on said frame for pivoting 40 the armature at its center to cause said end members to swing past said poles, a contact carried by said frame, a contact carried by said armature, a resilient support for one of said contacts, said contacts being arranged to make con- 45

tact and to energize said windings when the end members of the armature are in a position to be attracted by the poles, said resilient support breaking contact prior to the armature and members reaching fully attracted position to 5 cause the end members to coast past the poles, said resilient support and the contact carried thereby being confined to the space limited by sweep of the end members of the armature to permit rotation of the armature throughout an 10 angle greater than 180 degrees, and a spring acting between the frame and armature for urging the armature to rotate in a direction to close the circuit through the contacts.

2. A device for producing current pulses comprising an elongated open core having poles at the ends of the same, windings on the interior portion of said core, a base, means for securing said core and windings to the base, an armature constructed from a bar bent to form an 20 elongated body portion and end portions depending therefrom and disposed so as to cooperate with the ends of the core, a U-shaped frame member straddling said core and windings and secured to said base, said frame member being 25 of lateral dimensions less than the spacing of the end portions of the armature, said armature overlying said frame, means on said frame for pivoting the armature at its center to cause the end members of the armature to swing past said 30 poles and at one position straddle said frame, a contact carried by said armature, a contact carried by said frame, a resilient support for one of said contacts, said contacts being arranged to close and energize said windings when the end 35 members of the armature are in a position to be attracted by the poles, said resilient support breaking contact prior to the armature end members reaching fully attracted position to cause the end members to coast past the poles, said 40 resilient support and the contact carried thereby disposed within the space limited by the sweep of the end members of the armature outwardly of the frame to permit rotation of the armature throughout an angle greater than 180° and a 45 spring acting between the frame and armature for urging the armature to rotate in a direction to make contact between the contacts.

HENRY L. MILLS.
